DEAERATION AND DRYING OF WATER-SOLUBLE SULFONATED DETERGENT COMPOSITIONS

Earl Davis, Whittier, Calif., assignor to Purex Corporation, Ltd., South Gate, Calif., a corporation of California

Application June 9, 1950, Serial No. 167,086

9 Claims. (Cl. 252—161)

1

This invention has to do generally with the manufacture of detergents suitable for use as washing compounds, and particularly with the production of such compounded detergents by methods having for their major object to give to the final and marketable products desirable solubility properties and high bulk densities. While applicable broadly to the manufacture of detergent compositions in general and whose densities are subject to increase by deaeration of a dryable slurry containing the detergent, the invention will be described typically, though as illustrative only, with reference to detergents containing as active ingredients the alkali metal salts of organic sulfonates and sulfates having such molecular structures as to possess detergent properties.

It has been customary in the manufacture of such detergents to produce first an aqueous slurry of the alkali metal organic sulfonates or sulfates, to which are added one or more salts or additives such as soda ash, sodium bicarbonate, alkali metal silicate, borax, sodium sulfate, sodium chloride, fuller's earth and the like, to produce a mixture or slurry dryable to any final form, e. g. as by spray drying, drum drying, or tray drying. Considering spray drying as typical, it is desirable that the solid granules resulting from spray drying of the slurry, have a high bulk density, say upward of 0.40 or above. Now by the usual methods of slurry treatment and dehydration, potentially high bulk densities of final product either are not obtainable, or can be reached only as a result of relatively inconvenient and prolonged procedures.

It is found that lower densities of the final product generally are due to the presence of air in the mixture or slurry to be dried, and to the retention of the air in the dried product, as in the case of spray dried granules wherein the entrapped air tends to expand the particles and therefore lower their bulk density. My general object is to provide a simple and eminently practical method whereby in continuous operation an aerated slurry may be quickly and effectively deaerated to the degree desired, and the deaerated slurry then dehydrated and dried, as by a final spray drying operation.

In accordance with the invention, a slurry containing any suitable alkali metal sulfonates or sulfates possessing detergent properties (for example as more fully developed in a copending Stoneman application Serial Number 167,642, filed June 12, 1950), may be mixed with any of such solid additives as the builders and fillers referred to above. Merely as illustrative, the

2

organic detergent components of the slurry may include or consist of compounds of the general formula $R-SO_2-OH$, wherein R is any benzoid hydrocarbon radical having two or more replaceable nuclear hydrogen atoms (as derived from benzene, toluene or xylene), and at least one nuclear hydrogen atom replaced by aliphatic or alicyclic radical containing 8 to 18 carbon atoms. Examples are the alkali metal salts of n-dodecyl benzene sulfonic acid, n-dodecyl toluene sulfonic acid, undecane-2-benzene sulfonic acid, and in general mixtures of this class in which the 8 to 18 carbon alkyl radical is derived from aliphatic or alicyclic compounds of either straight or branched, symmetrical or non-symmetrical structure, such as may be found in distilled petroleum fractions or in other naturally occurring substances. Other contemplated detergents (mentioned also in the Stoneman application) include the sulfonic and sulfuric acid derivatives of the 8-18 carbon atoms olefins, alcohols, fatty acids, alkyl halides, and esters in the aliphatic or alicyclic series and mixtures thereof. Generally, the slurry to be deaerated prior to drying may be characterized with respect to its active content as containing an anionic, or mixture thereof, in the class of organic sulfonates or sulfates containing an aliphatic or alicyclic part which may or may not be attached to an aromatic ring, with the aliphatic or alicyclic part being derived from compounds containing 8-18 carbon atoms and capable of either direct reaction to the sulfates or sulfonates, or indirect reaction by combination with an aromatic ring part or radical.

Deaeration of the slurry preparatory to drying, is accomplished by passing the slurry through a zone maintained under subatmospheric pressure and within a range that may be regulated in accordance with the degree of deaeration desired. Typically, the deaeration chamber is maintained at an absolute pressure within the range of about 50 to 250 mm. As will appear, the invention contemplates an uninterrupted process whereby the admixed slurry and additives may be passed continuously from the mixer and thence through the deaerator to the spray drier.

A further object of the invention is to make higher density final products from a slurry produced by the method of my copending application referred to above, in accordance with which the alkali metal organic sulfonate results from neutralization under low pressure and under conditions such that the neutralized slurry going into the mixer, has been subjected to effective prelim-

inary deaeration. When operated in conjunction with this low pressure process of neutralization, the bulk of the air removed in the final deaeration stage is that introduced into the slurry in the mixing operation.

All the features and objects of the invention, as well as the details of an illustrative embodiment, will be more clearly understood from the following detailed description of the accompanying drawing illustrating a typical procedure diagrammatically and in flow sheet form:

While it is to be understood that in the broad contemplation of the invention, the slurry to be subjected to final deaeration preliminary to drying, may be produced in any suitable manner, there are advantages in so treating a slurry which has been subjected to prior deaeration during and as a result of a low pressure neutralization stage. For more complete details concerning the low pressure neutralization of a suitable sulfated or sulfonated detergent stock, reference may be had to the copending Stoneman application referred to above. For present purposes, it will suffice to refer to the neutralizing stage, generally indicated at 10, as comprising a neutralizing chamber 11 evacuated through head 12 connecting with a vacuum pump or steam ejector to maintain in the chamber an absolute pressure within the range of about 9 to 88 mm. of mercury and at a corresponding water vapor temperature range between about 50 to 120° F.

Chamber 11 communicates through line 13 with one or the other of the closed weigh tanks 15 and 16 which, should line 13 form a direct and unrestricted passage, are located below the neutralizer a distance such that the communication between the neutralizer and tank constitutes a barometric leg. This distance may be shortened by placing in line 13 a pump 17, the displacement rate of which is sufficient to permit maintenance of the stated low pressure in the neutralizer. At the start of the neutralizing operation, one or the other of the tanks 15 and 16 is charged with a weighed quantity of alkali, preferably caustic soda solution, a stream of which is constantly circulated through line 17 by pump 18 into a header 19 communicating with circularly arranged spray nozzles 20 in the head of the neutralizing chamber. The sulfonated hydrocarbon stream is fed at a predetermined rate through line 21 into a second header 22 which also connects with the spray nozzles 20. The sulfonic acids and alkali are premixed, reacted and sprayed into the neutralizer, and the resulting solution or slurry is taken through line 13 to the weigh tank. This cycle of alkali and slurry recirculation from the tank to the spray nozzles continues until a predetermined and stoichiometric quantity of the acids is neutralized by reaction with the alkali in the neutralizer. The neutralized slurry finally is withdrawn from tank 15 or 16 through line 24 for delivery to the mixer 25.

Suitable solid builders or fillers are added through inlet 26 to the slurry in the mixer and the components are subjected to thorough mixing as by a mechanically driven agitator diagrammatically indicated at 27. From typical operating data, it is found that the specific gravity of the neutralized slurry going to the mixer may be within the range of about 0.84 to 1.14. The sulfonated slurry after compounding with the additives in the mixer and containing for example 8 to 27% by weight of the neutralized active detergent, has an increased density with-

in the range of about 1.15 to 1.20. This slurry then is continuously withdrawn from the mixer through line 28 and discharged by pump 29 into a deaerating chamber 30 preferably in finely divided or sprayed form, as through a spray nozzle 31 in the head of the chamber. The latter is connected through line 32 with a suitable evacuator, so that the deaerator is operated under a pressure considerably below atmospheric pressure, and typically within the range of 50 to 250 mm. absolute. Ordinarily the temperature of the compounded slurry will be approximately atmospheric temperature. Being dispersed in finely divided form within the evacuated zone, the compounded slurry is effectively depleted of its air content, as well as some moisture, in accordance with the pressure existing in the deaerator, and its density is brought within the range of say 1.20 to 1.44.

The deaerated slurry is continuously withdrawn from the deaerator through line 33 and is discharged by pump 34 into a suitable drier 35, preferably of the spray type within which the slurry is reduced to finely divided form and dried by contact with hot gases or air, resulting in the production of the detergent as granulated particles. As previously indicated, the primary effect and advantage of the deaeration is the production of granules having higher bulk densities, this property apparently being due to the fact that whereas ordinarily the presence of air in the slurry being spray dried tends to remain entrapped and to expand therein, thus enlarging the hollow globular particles and thinning the shells, preliminary removal of the air in accordance with the invention enables the particles to dry in more compact and dense form, free from excessive air expansion.

I claim:

1. The method of producing an increased density solid detergent of the class consisting of synthetic anionic sulfated and sulfonated water soluble detergents, that comprises subjecting an air-containing fluid aqueous slurry of the detergent to deaeration, without drying at sub-atmospheric pressure in one zone, and then drying the deaerated fluid slurry in another independent zone to produce the detergent in solid form.

2. The method of producing an increased density detergent of the class consisting of synthetic anionic sulfated and sulfonated water soluble detergents, that comprises subjecting an air-containing fluid aqueous slurry of the detergent to deaeration, without drying at an absolute pressure between about 50 to 250 mm. of mercury in one zone, and then drying the deaerated fluid slurry in another independent zone to produce the detergent in solid form.

3. The method of producing an increased density detergent from an air-containing fluid slurry thereof of the class consisting of synthetic anionic sulfated and sulfonated water soluble detergents, that comprises deaerating, without drying the slurry by dispersing the slurry in divided and extensively exposed surface within a zone maintained at subatmospheric pressure, continuously withdrawing the deaerated slurry from said zone into a second zone, and then spray drying the fluid deaerated slurry in said second zone to produce the detergent in solid granular form.

4. The method of producing an increased density detergent of the class consisting of synthetic anionic sulfated and sulfonated water soluble detergents, that comprises mixing solid

additives with and thereby entraining air in an aqueous slurry of the detergent in a first zone, subjecting the resulting mixture to deaeration and partial dehydration, but without drying, at subatmospheric pressure in a second zone by dispersing the slurry in extensively exposed surface form into the evacuated atmosphere of the second zone and then spray drying the deaerated mixture in a third independent zone.

5. The method of producing an increased density detergent of the class consisting of synthetic anionic sulfated and sulfonated water soluble detergents, that comprises mixing solid additives with and thereby entraining air in an aqueous slurry of the detergent in a first zone, subjecting the resulting mixture in divided and extensively exposed surface form to deaeration, without drying at an absolute pressure between about 50 to 250 mm. of mercury in a second zone, and then spray drying the deaerated mixture in a third independent zone.

6. The method of producing an increased density detergent of the class consisting of synthetic anionic sulfated and sulfonated water soluble detergents, that comprises mixing solid additives with and thereby entraining air in an aqueous slurry of the detergent in a first zone, deaerating the mixture, without drying it, by spraying a slurry of the mixture within a second zone maintained at subatmospheric pressure, and continuously withdrawing and spray drying the deaerated slurry in a third independent zone.

7. The method of producing an increased density product detergent from an aqueous slurry of an alkali metal alkyl aryl sulfonate detergent, that includes mixing solid additives with said slurry in a first zone under conditions tending to aerate the slurry and thereby producing an aerated slurry having a density between about 0.95 to 1.20, deaerating, without drying, said aerated slurry in a second zone to a degree increasing its density to within the range of about 1.20 to 1.44, and finally spray drying the deaerated slurry in a third independent zone.

8. The method of producing an increased den-

sity detergent product from a detergent of the class consisting of alkyl aryl sulfonates having a benzene radical to which is attached an aliphatic radical containing between 8 to 18 carbon atoms, that includes mixing solid additives with an aqueous slurry of the detergent in a first zone under conditions tending to aerate the slurry and thereby producing an aerated slurry having a density between about 0.5 to 1.20, deaerating, without drying, said aerated slurry in a second zone to a degree increasing its density to within the range of about 1.20 to 1.44, and finally spray drying the deaerated slurry in a third independent zone.

15. The method of producing an increased density product detergent of the class consisting of synthetic anionic sulfated and sulfonated water soluble detergents from an aqueous slurry thereof that includes mixing solid additives with said slurry in a first zone under conditions tending to aerate the slurry, continuously discharging the aerated slurry through a second zone maintained at subatmospheric pressure below 250 mm. absolute pressure and therein removing the bulk of the air content of the slurry without drying the slurry, continuously pumping the deaerated slurry from the second zone into a third zone, and spray drying the slurry in the third zone to convert the slurry to dry granulated particles.
